UNITED STATES PATENT OFFICE.

MADS M. LARSEN, OF COLTON, CALIFORNIA.

AUTOMOBILE RADIATOR.

Application filed August 2, 1923. Serial No. 655,227.

To all whom it may concern:

Be it known that I, MADS M. LARSEN, a citizen of the United States, residing at Colton, in the county of San Bernardino 5 and State of California, have invented new and useful Improvements in Automobile Radiators, of which the following is a specification.

My invention relates to radiators for 10 motor vehicles and the like, and a purpose of my invention is the provision of a radiator of increased efficiency.

It is also a purpose of my invention to 15 provide a radiator which includes two units interconnected to allow the circulation of water from one unit to the other, and fans associated with the units for creating a forced circulation of air through the units. Another purpose of my invention is the 20 provision of a radiator having water pipes and air pipes constructed and arranged to develop maximum cooling efficiency.

I provide a double radiator having a rear unit and a front unit with a fan between, in 25 which the hot water circulating from the engine passes into the base of the rearward unit, passes up through the cooling tubes to an upper head and is conducted by a pipe to the upper head of a front radiator, passes 30 downwardly through this radiator and back to the engine by a pipe connected to the lower head of the front radiator, this pipe passing through the lower head of the rearward unit.

Although I have herein shown and will 35 describe only one form of radiator embodying my invention, it is to be understood that various changes and modifications may be made herein without departing from the 40 spirit of the invention and the spirit and scope of the appended claims.

In the accompanying drawings,

Fig. 1 is a view showing in vertical section one form of radiator embodying my 45 invention.

Fig. 2 is a view showing in front elevation a front unit of the radiator shown in Fig. 1.

Fig. 3 is a view showing in front elevation 50 the rear unit comprised in the radiator shown in Fig. 1.

Figs. 4 and 5 are transverse sectional views taken on the lines 4-4 and 5-5, respectively, of Fig. 1.

Fig. 6 is a perspective view somewhat dia- 55 grammatic showing the two units comprised

in the radiator and the manner in which the water circulates through the two.

Similar reference characters refer to similar parts in each of the several views.

Referring specifically to the drawings and 60 particularly to Fig. 1, 15 designates a metallic casing in which the units, designated generally at T and T' comprised in the radiator embodying my invention, are arranged, the forward unit being preferably spanned by a foraminous sheet 16 of wire screen or the like for a purpose which will be hereinafter described. The screen 16 65 may be secured in the forward end of the casing 15 in any suitable manner, and, in the present instance, the casing is formed with an inturned flange 17 beneath which the screen is secured. The front unit T is adapted to be permanently secured within the casing 15 in any suitable manner, while the rear unit T' is removably arranged in the casing to allow separation of the two 70 units for repairing or other purposes.

The front unit T is made up of a water 75 jacket including an upper head 18 having side columns 18' and 18" and a lower head 19 connecting the lower ends of the side columns 18' and 18", and this jacket is provided with a multiplicity of openings in 80 which are secured pipes 20 through which air is adapted to circulate in effecting the cooling of the water within the jacket. As clearly shown in Fig. 2, the water jacket is 85 of substantially rectangular form so as to provide a square opening 21 which is traversed at spaced intervals by conduits 22 through which water from the upper head 18 is adapted to circulate to the lower head 19. These conduits 22 are of triangular 90 form in cross section, as clearly shown in Fig. 4, and any two adjacent conduits are arranged so that their wide edges are disposed at opposite sides of the water jacket, thereby producing an intervening space the 95 transverse axis of which is disposed diagonally. Any two adjacent intervening spaces are arranged in converging or diverging relation to each other so that the passage of air between the conduits is adapted 100 to be retarded, as will be more fully described hereinafter.

The rear unit T' includes a water jacket 105 having an upper head 23 side columns 23' and 23" extending downwardly from the head, a lower head 24 connecting the lower ends of the side columns 23' and 23" and

an intermediate head 25 connecting the intermediate portions of the side columns 23' and 23^a. This water jacket is of the same shape and outline as the water jacket of the front unit, and it is also provided with air conducting pipes 19 and water conduits 22, the latter being constructed in the same manner as the first water conduits and arranged vertically within the spaces 26 and 27 of the water jacket between the heads 23, 24 and 25. It will be noted that the head 25 is also provided with air pipes 19 and with an opening 28 (Fig. 1) in which is fixed a bearing block 29 having a sleeve 30 through which extends a tubular shaft 31. The forward end of the shaft is provided with a fan 32, and a second fan 33 is fixed to the shaft at the rear of the unit T' and in advance of a bearing 34 formed in the upper end of a standard 35 and provided with a sleeve 36 for the reception of the shaft. A grooved pulley 37 is fixed to the shaft 31 at the rear of the bearing 34, and a lubricating cup 38 is in communication with the rear end of the shaft 31 for the purpose of supplying a lubricant to the bearing sleeves 30 and 36 through the shaft. Openings 39 and 40 are formed in the shaft 31 to allow the passage of the lubricant from the shaft to the bearing sleeves.

The standard 35 is secured to a casing 41 which embraces the rear cooling unit T', and which is of such a size as to fit within the casing 15.

As clearly shown in Figs. 1 and 6, the upper heads 18 and 23 of the units T and T' are in communication with each other through a pipe connection 42 provided with a union 43 which allows of the disconnection of the sections when desired.

The radiator when in applied position to an internal combustion engine is adapted for connection to the pump of the cooling system through a pipe 44 so that water is first supplied to the rear cooling unit T'. The water now circulates through the jacket of this unit and upwardly through the connection 42 into the upper head 18 of the front cooling unit. From the head 18, the water traverses the jacket and the conduits 22 from whence it is discharged into a pipe 45 in communication with the lower head 19. This pipe 45 is extended through a suitable opening formed in the jacket of the rear unit T', and is adapted for connection to the water jacket of the gas engine.

In order to provide access to the connection 42, and to provide further means by which cool air may be supplied to the rear cooling unit T', the casing 15 is formed with openings 46 spanned by plates 47 removably secured to the casing and formed with openings 48 through which air can pass into the casing and between the units T and T'. It

will, of course, be understood that the water jacket of the front cooling unit T can be supplied with water through a spout 49 normally closed by a cap 50.

In practice, the shaft 31 is adapted to be driven from the internal combustion engine by applying a fan belt to the pulley 37 so that the fans 32 and 33 are continuously rotated to effect the forced circulation of air through the pipes 20 and the spaces between the conduits 22. Because of the tapered formation of the conduits 22, the passage of air between the conduits is retarded sufficiently to fully utilize the heat dissipating property of the air, and in conjunction with the cooling property of the air pipes 20, a radiator of maximum cooling efficiency is produced.

It will be understood that the air produced by the operation of the fans not only traverses the conduits and pipes of the front cooling unit, but also the pipes and conduits of the rear cooling unit, thereby securing a further cooling of the water. This combined cooling action of the units T and T' has been found in practice to be sufficient to maintain at all times the temperature of the water below a boiling point.

It will be noted, referring particularly to Fig. 6, that the circulation of hot water from the engine enters by the pipe 44 into the lower head 24 of the rearward radiator, passes up the tubes, through the cross head 25 to the upper head 23. The pipe 42 carries the water then to the head 18 of the front radiator, the water circulating downwardly and out by the pipe 45 which passes through the rear unit and back to the engine.

It will thus be seen that the circulation in the rear unit is the reverse of that usually utilized in radiators of internal combustion engines, this action, however, of the hot water directly from the engine rising in the radiator gives greater impetus or force to the circulation of the water and allows the thermo-siphon type of cooling to be used with large entrance requiring the extraction of a large amount of heat. With the double radiators connected as shown reliance is not merely placed on the changes of density of the water in the base and top of the engine and the down flowing current due to the increased density in the radiator.

What I claim is:

1. A radiator, comprising a pair of water jackets arranged one in the rear of the other and interconnected, a casing surrounding the water jackets and having openings therein through which access may be had to the connections between the jackets, and perforated doors controlling said openings.

2. A radiator having two water units with radiating elements spaced apart each of the units including a head, water columns ex-

- tending downwardly from the head and a lower head connecting the lower ends of the water columns, there being a multiplicity of horizontal openings through the heads and 5 water columns, an additional head extending transversely across the rear unit and having an aperture therethrough for a shaft; a pipe leading to the lower head of the rear unit only from the source of supply, a second 10 pipe connecting the upper heads, a third pipe leading from the lower heads of the front unit only to the source of supply, said pipe passing through an opening in the rearward unit.
- 15 3. A radiator having two independent water jacket radiator units, the rear unit comprising an upper head, water columns extending downwardly from the upper head, a lower head connecting the lower ends of 20 the water columns, an intermediate head connecting the intermediate portions of the water columns, there being a multiplicity of horizontal openings through the upper head, the water columns, the lower head and the intermediate head, and pipes secured in the 25 openings.
4. A radiator having two independent wa-
ter jacket radiator units, the rear unit com-
prising an upper head, water columns ex-
tending downwardly from the upper head, 30
a lower head connecting the lower ends of
the water columns, an intermediate head
connecting the intermediate portions of the
water columns, there being a multiplicity of
horizontal openings through the upper head, 35
the water columns, the lower head and the
intermediate head, and pipes secured in the
openings, there being a bearing block fixed
through the center of the intermediate head,
a shaft rotatably mounted in the bearing 40
block, a fan between the water jacket radiat-
ing units upon the shaft, and a second fan
behind the rear water jacket radiating unit.

In testimony whereof I have signed my
name to this specification.

MADS M. LARSEN.
